WINDOW SHADE AND SUPPORTING
BRACKETS

Frank R. Schueller, Cincinnati, Ohio, assignor to
The Chas. W. Breneman Company, Cincinnati,
Ohio, a corporation of Ohio

Application January 5, 1944, Serial No. 517,123

5 Claims. (Cl. 248—267)

This invention relates to brackets for supporting window shades and is directed particularly to an improved structure which is more durable and more attractive in appearance than those heretofore available.

The conventional shade brackets are sheet metal stampings, each having a foot through which it is mounted on the window frame while one of the brackets of a pair has a slot to receive the spear projecting from one end of the shade roller, and the other bracket has a bore or opening to receive the pin extending from the shade roller at its other end. The shade roller has brass ferrules covering its endwise portions which, in most instances, not only protect the wooden roller but help support the pin and tang projections, also cooperating with the rewinding mechanism of the roller. In the usual mounting, the ferrules are unsightly and the mechanical connection of the roller with the brackets is not pleasing in appearance.

The objective of this invention principally has been to provide a structure in which a housing covering the ferruled endwise portion of the shade roller is interposed between the bracket and the spear or pin, as the case may be, to serve the purpose of forming the structural supporting element by which the endwise portion of the roller is interconnected with the bracket, to conceal the ferrules and improve the visual appearance of the assembly, and to protect the journals and roller rewind mechanism against dust.

The outer periphery of the cover or cap, as it may be called, is substantially the same in diameter as the diameter of the shade roller when the shade has been wound substantially upon it. Therefore, the outer surfaces of the shade and cap are substantially flush with one another, the cap in effect forming a continuation of the rolled up shade, which is pleasing in appearance. The inward face of this cap is adjacent the edge of the shade and also serves to some extent as a guide therefor. In the mechanical structure of the apparatus the cap is a cup-like element which fits over the end of the shade roller while a recess or cavity is provided at the bottom of this piece to receive the spear or pin. The outside of this portion of the cap is squared or grooved to fit within a slot or opening of similar configuration in the bracket. In this manner, therefore, the bracket supports the cap and the cap, in turn, supports the shade roller. The structure also may be provided with a roller for guiding the edgewise portion of the shade so that it may be rolled up evenly.

Other features of the invention and further objectives are discussed in the drawing in which preferred embodiments of the improvement are illustrated.

5 In the drawing:

Figure 1 is a fragmentary view of the upper part of a window showing a shade roller and brackets, in accordance with the present invention, mounted thereon.

Figure 2 is an enlarged elevation showing the assembly of the shade roller, cap and bracket in working position.

Figure 3 is an endwise elevation of the bracket and cap.

15 Figure 4 is a longitudinal sectional view taken through the brackets and caps and also shows the shade roller mounted therebetween.

Figure 5 is an exploded perspective view showing the bracket and cap disassembled.

The brackets of the present invention are adapted to be mounted in the conventional way. As shown in Figure 1, they are fastened upon a window frame indicated generally at 1 at the upper portion thereof to support a shade roller 2 therebetween. The shade roller and shade thereon, as referred to in this specification, may be of the usual type and therefore they are not described in detail.

30 Each bracket assembly consists of two parts, the bracket proper designated 3, and the cap or cover which is indicated generally at 4. The bracket, as shown best in Figure 5, generally is similar to those heretofore employed and consists of an arm portion 5 and a foot portion 6 which extends laterally with respect to the arm and which is adapted to be mounted upon the window frame by means of screws 7. The brackets of the present invention, however, differ from those which are conventional in that the apertures 8 in the arms thereof are openings of substantial size and in effect constitute cradles for the caps 4 through which the caps are held in non-rotatable relationship thereto.

45 Each cap has a cup-shaped portion 9 which fits over the end of the shade roller to conceal the ferrule portion thereof. This is shown best in Figure 4, the cavity in the cap in which the endwise portion of the shade roller resides being designated 10. The outside diameter of this portion of the cap is substantially the diameter of the shade roller when the shade has been wound substantially upon it, so that the cap in effect constitutes a continuation of the shade roller.

50 In the bottom wall 11 of the cavity 10 a recess 12 is provided. This recess in the cap which is

to fit over one end of the shade roller is an oblong recess as shown in Figure 4, configurated to receive the spear or tang 13 of the roller; the cap for the opposite end may have a circular hole to receive the shade roller pin 14.

Each cap has a circular projection or boss 15 extending from the cup-shaped portion 9 thereof. This portion preferably, though not necessarily, is of smaller diameter than the cup portion, and grooves 16 are cut into the sides thereof at a distance spaced inwardly from the end. These grooves on each cap delineate a neck which fits within the opening 8 of the bracket. In the preferred structure, grooves 17 are cut across the bottoms of the bosses 15 to provide flat seats upon which the caps may rest within the brackets. It may be seen, therefore, that the cap is held against rotation by the squared portion constituted by the grooves while the uncut portion of the cap boss 15 beyond the grooves constitutes a flange which holds the cap in the bracket.

For the purpose of assisting in the guiding of the shade roller when it is being rolled and unrolled the brackets may be provided with supplemental guide rollers 18 which are positioned to be engaged by the sidewise edges of the window shade and thereby direct the shade in an even rolling action. One end of each roller 18 is journaled in a bore 19 in the foot 6 of the bracket while the other end is journaled in a boss 20 extending from the arm 5. The rollers are inserted through bore 19 prior to fixing the bracket to the window frame.

To mount a window shade in accordance with the present invention the brackets are put up in the usual way but are spaced apart a distance sufficiently to accommodate the caps mounted on the ends of the roller. After the brackets have been fastened a cap is placed in one of the brackets, the shade is inserted within that cap, then the other cap is placed upon the other end of the shade which is next lowered into the bracket.

The devices may be made either of sheet metal or of plastic materials as desired. By virtue of the fact that the end of the spring at the end of the roller to which the spring rewind mechanism is located is fully concealed by the cap, dust and dirt are excluded from the rewind mechanism and the entire structure in appearance presents an apparatus of pleasing contour.

Having described my invention, I claim:

1. The combination of a bracket having a foot portion adapted to be fastened to a wall and an arm portion extending laterally therefrom and

having a slot of substantial width extending transversely therethrough, and a shade supporting member having recesses therein arranged to fit within said transverse slot and a cup-shaped portion extending therebeyond, the said shade supporting member being configurated to extend over the ferruled endwise portion of a window shade roller, and the said cup-shaped portion thereof having a recess at its bottom for receiving the tang or spear of a window shade roller.

5. The combination of a bracket, comprising an arm portion having a slot extending transversely therethrough and communicating with an edge thereof, and a cap member comprising a hollow cylindrical portion arranged to extend substantially over the endwise portion of a window shade roller and having a recess extending therein laterally to the axis thereof through which said cap member may be received within the transverse opening of said bracket.

15. The combination of a window shade bracket, which includes an arm having a laterally extending gap of substantial width near the outer extremity thereof, a substantially cylindrical member having opposed slots adjacent one end thereof through which said member may be received within said gap, and having a cylindrical cavity of substantial depth for reception of the endwise portion of a window shade therein, with a recess 25 at the bottom of said cavity configurated to receive the shade roller spear or tang.

20. The combination of a window shade bracket, including an arm having a gap of substantial width extending transversely therethrough and open at an edge thereof, and a cap member having at least one lateral groove therein through which said cap may be received within said gap, and also having a cylindrical cavity extending longitudinally therein from one end to a substantial depth for reception and concealment of the endwise portion of a shade roller, and a second recess extending beyond the first to receive the shade roller spear or tang.

25. As a new article of manufacture for use with a window shade and bracket, comprising a cap adapted to extend for a substantial distance over the endwise portion of a window shade roller, the said cap having a recess at the bottom thereof forming a supporting connection between the cap and the spear or pin extending from the shade roller and having at least one slot extending laterally into the body thereof through which said cap may be received and held against rotation in the gap of a shade roller bracket.
